CLAIM

The ornamental design for a rectangular table with a triangular surface pattern, as shown and described.

DESCRIPTION

FIG. 1 is a perspective view of a rectangular table with triangular surface pattern, showing my new design.

FIG. 2 is a side elevational view along one side thereof;

FIG. 3 is a side elevational view along the other side thereof;

FIG. 4 is a top plan view thereof;

FIG. 5 is a bottom plan view thereof;

FIG. 6 is a bottom plan view thereof with the legs in stored position;

FIG. 7 is an enlarged perspective view of a second embodiment of my new rectangular table with a triangular surface pattern;

FIG. 8 is an enlarged top plan view of the embodiment of the rectangular table with triangular surface pattern of FIG. 7; and,

FIG. 9 is a side sectional view along the lines 8—8 of FIG. 8.
